UNITED STATES PATENT OFFICE.

HENRY D. BARAGWANATH, OF CHICAGO, ILLINOIS.

BAROMETRIC CONDENSER.

No. 868,577.

Specification of Letters Patent.

Patented Aug. 20, 1907.

Application filed May 11, 1906. Serial No. 316,397.

To all whom it may concern:

Be it known that I, HENRY D. BARAGWANATH, a citizen of the United States of America, and a resident of Chicago, in the county of Cook and State of Illinois, have invented certain new and useful Improvements in Barometric Condensers, of which the following is a specification.

The main object of this invention is to provide an improved form of ejector condenser of the barometric type, having a dry air pump connection for exhausting air from the condenser at a point below the narrowest point of the throat, thereby largely increasing the efficiency of the condenser with a minimum quantity of water.

15 This object is accomplished by the device shown in the accompanying drawing which represents a vertical section, partly broken away, of a barometric condenser constructed according to this invention.

In the construction shown in the drawings, the usual vertical steam pipe 1 is provided at its upper end with a double elbow 2 so that the steam is discharged in a downward direction. A relief valve 3 is provided at the upper end of the steam pipe 1, and is adjusted to permit the escape of steam when a certain normal pressure is exceeded. The elbow 2 discharges into a steam funnel 4 which is mounted in alignment therewith and is vertically adjustable by means of the hand wheel 5 and stem 6 which is threaded into a yoke 7 at the upper end of the funnel 4. A steam and water mixing funnel 8 is secured in direct alignment with the steam funnel 4.

The upper end of the funnel 8 is surrounded by a casing 9 which connects said funnel with the elbows 2. The condensing water is supplied to the casing 9 by the pipe 10 and is admitted to the funnel 8 at the inlet 11 around the edges of the steam funnel 4. The area of the inlet 11 is controlled by adjusting the funnel 4 vertically with respect to the funnel 8. An ejector throat 12 is secured to the lower end of the funnel 8 and forms an unbroken continuation thereof. The throat 12 is gradually contracted in transverse area until it reaches a minimum at a point intermediate of its ends, preferably closer to the lower end than to the upper end and the area is then gradually increased toward the discharge end as is usual in the throats of injectors and ejectors. As is well known a throat of this shape along which steam and water are delivered in a longitudinal direction causes the discharge of a much greater quantity of steam or water than would be the case if the throat were not so contracted. The throat 12 is surrounded by a second casing 13 which communicates at its lower end with a barometric tail pipe 14. The upper end of the tail pipe 14 is located 33 feet above the level of the water in the hot well, so that under no circumstances can the water ever rise to a sufficient height

55 to submerge the lower end of the throat 2. The internal diameter of the pipe 14 is, throughout its length to

the hot well, greater than the internal diameter of the ejector throat 12, so as to permit all water passing through the throat 12 to be freely and rapidly carried down. The casing 13 is connected by means of a pipe 60 15 with a dry air pump which exhausts the air from the casing 13 and produces a vacuum below the discharge end of the throat 12. The flange 16 at the upper end of the throat 12 forms the upper end of the casing 13 and serves as a closure for preventing communication 65 between the dry-air pump connection 15 and the steam and water inlets except through the lower end of said throat.

The operation of the device shown is as follows: Steam enters the condenser from the pipe 1 and passes 70 directly downward through the funnel 4. Water entering the casing 9 from the pipe 10 is discharged in a thin sheet around the lower edges of the funnel 4. The steam and water mix in the funnel 8 and pass through the ejector throat 12 at a high velocity. The water 75 then passes into the barometric tail pipe 14 by which it is carried to the hot well. The tail pipe 14 is of considerably greater diameter than the throat 12, being usually about twice such diameter. The dry air pump exhausts the air which has been carried through the 80 throat 12 by the steam and water. This greatly increases the efficiency of the condenser, and permits of the use of a small amount of water in the tail-pipe 14 and in the hot-well.

What I claim as my invention and desire to secure by 85 Letters Patent is:

1. A barometric condenser comprising a combined steam and water mixing funnel, an elongated gradually contracted ejector throat below said funnel and forming an unbroken continuation thereof, a casing surrounding the 90 said throat and having a barometric outlet pipe communicating therewith below the discharge end of said throat, and an air outlet communicating with said casing above the discharge end of said throat and adapted to draw the air from said funnel below the discharge end of said 95 throat.

2. A barometric condenser comprising a combined steam and water mixing funnel, an elongated gradually contracted ejector throat below said funnel and forming an unbroken continuation thereof, a casing surrounding the 100 said throat and having a barometric outlet pipe connected thereto below the discharge end of said throat and having a greater internal diameter, throughout its length, than the contracted part of said throat, and an air outlet communicating with said casing above the discharge end of 105 said throat and adapted to draw the air from said funnel below the discharge end of said throat.

3. A barometric condenser comprising a casing having steam and water inlets, an elongated gradually contracted ejector throat mounted in alignment with said steam and water inlets, a barometric outlet pipe in alignment with said throat, dry air pump connection communicating with said casing above the discharge end of said throat and adapted to draw air from below the discharge end of 110 said throat, and a closure preventing communication between said connection and said inlets except through the discharge end of said throat.

4. In a condenser, the combination of a case divided into upper and lower chambers and having steam and water inlet connections opening into the upper chamber and an air-exhaust connection leading out of the upper part of the lower chamber, a funnel leading from the upper into the lower chamber, said funnel having its upper end extending above the bottom of the upper chamber and having its lower part extended to form an elongated contracted ejector throat, and a barometric outlet pipe leading out of the lower part of said chamber. 25
5. The lower chamber, a casing surrounding said steam-inlet funnel and the upper part of said ejector tube and having a water inlet, a casing surrounding the main lower part of said ejector tube and having connection at its lower end with a barometric discharge pipe, and an air-exhaust connection to said lower casing at a point above the lower end of said ejector tube. 30
6. In a condenser, the combination of a casing divided into upper and lower chambers, and having steam and water inlet connections opening into the upper chamber, said steam inlet connection being vertically adjustable, a funnel leading from the upper chamber into the lower chamber, said funnel receiving steam and water from said inlets, and having its lower part extended to form an elongated contracted ejector throat, an air-exhaust connection leading out of the upper part of the lower chamber, and a barometric outlet pipe leading out of the lower part of said chamber. 35
7. In a condenser, the combination of a casing divided into upper and lower chambers, and having steam and water inlet connections opening into the upper chamber, said steam inlet connection being vertically adjustable, a funnel leading from the upper chamber into the lower chamber, said funnel receiving steam and water from said inlets, and having its lower part extended to form an elongated contracted ejector throat, an air-exhaust connection leading out of the upper part of the lower chamber, and a barometric outlet pipe leading out of the lower part of said chamber. 40
8. A barometric condenser having steam and water inlets, a steam funnel receiving steam from the former; an ejector throat adapted to mix and discharge the steam and water from said inlets, the upper end of said throat lying close to the lower edge of said funnel, a barometric outlet pipe adapted to convey the water discharged by said throat, and an air outlet, communicating with said barometric outlet pipe above the discharge end of said throat and adapted to draw air from the discharge end of said throat and exert a suction in said throat in the direction of its discharge. 45
9. A barometric condenser comprising an elongated and downwardly tapered ejector tube, a vertically adjustable steam-inlet funnel adapted to discharge steam into said

Signed at Chicago this 9th day of May 1906.
